UNITED STATES PATENT OFFICE.

HARRY E. DOWNING, OF DEL NORTE, COLORADO.

INTERNAL-COMBUSTION ENGINE.

Application filed August 28, 1923. Serial No. 659,818.

To all whom it may concern:

Be it known that I, HARRY E. DOWNING, a citizen of the United States, and a resident of Del Norte, in the county of Rio Grande and State of Colorado, have invented certain new and useful Improvements in Internal-Combustion Engines, of which the following is a specification.

This invention relates to internal combustion engines and has for its object the provision of a device which is adapted to stop the engine when the lubricating pump fails to work.

A further object of the invention is the provision of a device adapted to be connected with an internal combustion engine for cutting out the ignition when the lubricating pump fails to work and for giving visual signals at the same time.

This invention will be best understood from a consideration of the following detailed description, in view of the accompanying drawing forming a part of the specification; nevertheless it is to be understood that the invention is not confined to the disclosure, being susceptible of such changes and modifications, which shall define no material departure from the salient features of the invention as expressed in the appended claim.

In the drawings:

Figure 1 is a fragmentary view partly in section of an automobile disclosing my invention in cooperative relation with an internal combustion engine of the automobile.

Figure 2 is a fragmentary plan view of the dash disclosing certain visual signals.

Figure 3 is a side view of the unitary structure for cutting out the ignition when the pump fails to work.

Figure 4 is a sectional view of the casing of the indicating mechanism shown in Figure 3.

Figure 5 is a vertical section of the casing and pump plunger operated by oil pressure.

Figure 6 is a view in section of the device shown in Figure 5 and with a section taken along the plane at right angles to the section shown in Figure 5.

Figure 7 is a view in perspective of the indicating plunger of the signalling device.

Figure 8 diagrammatically shows the wiring of the engine connected with the signalling device.

Referring more particularly to the drawings, 1 designates an internal combustion engine having spark plugs 2 which form part

of the ignition system of the engine. Wires 3 connect the spark plugs with a distributor 4.

Upon the dash 5 of the automobile is projected the face plate 6 of the indicator 7. This face plate is made of glass or some transparent material through which the indicia 8 "Off" is displayed and which is inscribed upon the outer face 9 of the plunger 10.

The plunger is reciprocable in a barrel 11 having a conduit 12 connected with the discharge end of the pump 13. A return conduit 14 incorporated in the cylinder 11 has 70 its one end 15 spaced from the glass 6. The conduit 14 is connected with a pipe 16 for returning oil back to the pump. The plunger 10 is provided with a reduced portion 17 which is encircled by a coil spring 75 18 for maintaining the plunger at the outer end of its stroke with the portion 9 adjacent the glass 6. The inner end of the spring abuts a shoulder 19 of the cylinder 11.

A metal ring 20 is connected to the reduced portion 17 of the piston and insulated from said piston by means of rings of insulating material 21. The movable contact members 22 and 23 are slidable in an insulated bearing 24 mounted in perforations in the reduced portion 25 of the cylinder 11. The contact 22 is electrically connected with the battery 26 while contact 23 is connected with the wire 27 leading to the ignition system. 90

A switch 28 having contact members 29 is adapted to span the outer end of the reduced portion 25 in the cylinder 11 and engage the contact members 22 and 23 for maintaining the circuit closed when the plunger 10 is moved to the outer end of the cylinder 11 and the oil pump is not working. These contacts are only temporarily moved into engagement with the contacts 22 and 23 when the handle 30 is pulled outwardly against the tension of the spring 31 and this handle is only withdrawn when the operator of the car presses his foot upon the usual means for starting the motor. Without the switch 28 and its respective 100 contact 29 the ignition circuit would be always broken. The handle 30 is insulated, as shown at 32, from switch 28.

The operation of my device is as follows:

When it is desired to start the motor, the usual button is depressed for starting the usual electric motor to rotate the engine

and at the same time the handle 30 is pulled outwardly from the front of the cylinder 9 in order to make contact between member 29 and the contacts 22 and 23, respectively. 5 This closes the circuit to the ignition and as soon as the engine is operated and the oil pump is working oil will be forced through passage 12 between plate 6 and the outer face 9 of the piston 10. The pressure 10 of the oil is sufficient to overcome the tension of the spring 18 and force the piston rearwardly until the oil is discharged through the return conduit 14. At this time the metallic ring 20 on the end of the piston 10 engages contacts 22 and 23 and maintains the ignition circuit closed. The handle 30 may then be released and the contacts 22 and 29 will become disengaged from contacts 22 and 23 since it is no longer necessary to maintain the circuit closed by the switch 28.

If anything should happen to the oil pump or a conduit should break or become clogged and the oil pump fails to supply the engine with lubricating oil, the flow of oil to the passage 12 and likewise to cylinder 11 will be cut off and the spring 18 will return the piston to the forward end of the cylinder and adjacent the plate 6. The

indicia "Off" will engage the transparent plate 6 and indicate that the oil pump is not working. At the same time the ignition circuit is broken since the plunger has been moved forwardly and released the ring 20 from the contacts 22 and 23. 35

What I claim is:

In an internal combustion engine having an ignition system, a circuit breaker comprising a cylinder adapted to be supplied with lubricant under pressure, a piston 40 movable in the cylinder and acted upon by the lubricant, a stem on the piston, contacts spring pressed towards the stem at diametrically opposite points on the stem and in circuit with the ignition system, a 45 contact adjacent each of the spring pressed contacts adapted to be manually operated and moved into engagement with the spring pressed contacts for closing the circuit, a glass window at one end of the cylinder, 50 said head of the piston having such indicia as "Off", the lubricant under pressure maintaining the piston head away from the glass window, and a spring forcing the piston head in engagement with the window to 55 disclose the indicia when the lubricant fails to retain the piston away from said window.

HARRY E. DOWNING.
